UNITED STATES PATENT OFFICE.

ROLAND MORRILL, OF BENTON HARBOR, MICHIGAN.

SPRAYER.

SPECIFICATION forming part of Letters Patent No. 691,651, dated January 21, 1902.

Application filed June 14, 1901. Serial No. 64,571. (No model.)

To all whom it may concern:

Be it known that I, ROLAND MORRILL, a citizen of the United States, residing at Benton Harbor, in the county of Berrien and State of Michigan, have invented certain new and useful Improvements in Sprayers, of which the following is a specification.

The present invention relates to sprayers of the class used for spraying plants, shrubs, trees, and other vegetation with insecticidal solutions.

More particularly stated, it relates to what may be called an "extension-nozzle" for sprayers intended for spraying high bushes, vines, trees, &c. In sprayers of the class described it is desirable to confine the spray to a comparatively small local area, or at any rate it is frequently desirable to do so, and these small local areas may be far above or beyond the reach of the operator. In tree culture, especially, this is the case. It may be desirable to spray a single infested bough or a portion of a bough, and this may be so far above or beyond the reach of the operator that either the pressure of the apparatus is insufficient to carry the spray to it through the atmosphere, or else if the pressure is sufficient the spray will be diffused over an unnecessarily large area—an area larger than that actually infested. In such cases it is desirable to have a nozzle which has sufficient lateral strength to sustain its own weight and which is of sufficient length to enable the operator to place its discharge end in close proximity to the part of the tree or vine or bush to be sprayed. These extension-nozzles are sometimes ten or twelve feet in length.

The object of this invention is to provide an extension-nozzle of improved construction—improved to the end that it shall be light, strong, and durable. To these ends I construct the nozzle of two fittings—an inner tube for the solution, connecting them, and an outer jacket or sheathing so connected to the fittings that it cannot turn relatively to them or to the inner tube.

To these ends the invention consists in the features of novelty that are herein described.

In the accompanying drawings, which are made a part of this specification, Figure 1 is a side elevation of a stop-cock and nozzle em-

bodying my invention. Fig. 2 is a longitudinal section thereof on a larger scale, an intermediate portion of the nozzle being broken away.

A represents a casting which at one and the same time serves as the casing of the stop-cock and the fitting for the base of the extension-nozzle. This casting has the general outline of a cross, comprising a longitudinal branch a' and a transverse branch $a^2 a^3$. The longitudinal branch has a bore through it from end to end. At one end a of the longitudinal branch it has a cup-shaped enlargement adapted to receive the connection from the source of supply, while at the other end it has the features, hereinafter described, adapted to receive the other parts going to make up the extension-nozzle. The transverse branch has a tapering bore adapted to receive a correspondingly-tapering plug B, having a single transverse part b , so that in one of its positions it obstructs while in another position, ninety degrees removed from the first, it leaves open the longitudinal bore. At one end the plug has a thumb-wing B' , and at the other end it has a reduced threaded portion b' , adapted to receive a nut C, which bears against the end of the transverse branch a^3 and holds the plug firmly seated in its tapering socket. It is found in practice that the grit in the solutions used soon causes leakage at the joint between the plug and the end a^3 of the transverse branch of the casing, and in order to prevent this I provide the said end a^3 of the transverse branch of the casing with an external thread adapted to be engaged by corresponding internal threads on a cap D, which at its outer end is made non-circular for the reception of a wrench by which it may be put in or removed from place. This cap completely covers the smaller end of the plug and prevents leakage of the solution onto the outside of the casing however loose the joint may be.

The branch a' of the casting A forms one of the fittings of the so-called "extension-nozzle," the other of said fittings being shown at E. The branch a' terminates in a tapering nipple a'' , surrounded by an annular flange a''' , which flares internally, so that between the nipple and flange there is left an

annular chamber, which in a longitudinal section of the casting appears to be of truncated V shape.

5 G is a light metal tube, one end of which is inserted in the bore of the branch a' of the casting A and permanently secured therein by solder or other suitable means, and the other end of which is passed through the bore of the fitting F and similarly secured.

10 H is a hollow non-metallic sheathing which forms a part of the extension-nozzle and gives it the necessary rigidity, while not making it objectionably heavy.

15 I am not the first to construct an extension-nozzle of an inner tube, such as G, and an outer sheathing, such as H; but I believe that I am the first to so associate these parts that the tube and sheathing are incapable of movement (and especially rotary movement) relatively to each other.

20 As heretofore arranged and connected they have been capable of rotary movement independently of each other, so that in the process of screwing the rose or equivalent tip onto or off of the fitting E the

25 inner tube G has been subjected to a torsional strain which was in no way resisted by the outer sheathing, because of the comparative independence of the two, at least so far as twisting or torsional strains were concerned.

30 As a result of this independence it has been a common occurrence to split or break in two the inner tube G by the simple act of applying or removing a rose or tip. In order to avoid this, I permanently and rigidly attach

35 the outer sheathing H to the two fittings at the opposite ends of the inner tube G, so that the several parts make a composite whole and so that neither the tube nor the sheathing can twist without the other twisting correspondingly.

40 To this end I preferably use for an outer sheathing a continuous piece of bamboo, the "joints" g of which are preferably bored the exact diameter of the tube G, so that they form braces for supporting said tube.

45 The larger end of this piece of bamboo, which is to join the casting A, is dressed off, so that it exactly fits the truncated V-groove of the fitting A. The other end of this bamboo pole fits in an annular socket formed in the fitting

50 E as the result of a tapering nipple f and a ferrule F' surrounding it and soldered or otherwise secured to the cast portion of the fitting. Having driven the reamed-out end of the elastic non-metallic sheathing H into

55 the truncated V-shaped groove between the nipple a'' and the flaring flange a''' , the outer margin of a collar or extension-flange I, of ductile metal, (previously secured to the flange a''' by solder or other suitable means,) is turned or crimped inward against and closely in contact with the sheathing H, so that the latter cannot twist or turn about its axis relatively to the branch a or the tube G in response to torsional strains put upon it.

60 65 As before stated, the part A is a casting, and not being ductile its flange a''' cannot be

turned or spun inward to engage the sheathing H, and this is the reason for making the extension of this flange of a separate piece of ductile metal, preferably sheet-brass, which 70 can be soldered or otherwise permanently secured to the flange a''' and may be spun or crimped or otherwise deflected inward so as to engage and take a firm hold upon the sheathing H. In similar manner the fitting 75 E is permanently secured to the sheathing H, so that the two are incapable of movement relatively to each other, especially about their longitudinal axis. Preferably the main part of the fitting E is a casting and the collar or 80 ferrule F' is of ductile material, the two being secured together by solder or other suitable means after the ferrule is attached to the sheathing, which may be done by any suitable means, but preferably by spurs f' , produced by a prick-punch.

Having described my invention, what I claim as new therein, and desire to secure by Letters Patent, is—

1. An extension-nozzle for sprayers having 90 a liquid-tube, a pair of fittings, one secured to each end of said tube, a sheathing surrounding the tube and extending from one of said fittings to the other, and means for non-rotatively securing the ends of the sheathing 95 to the fittings, respectively, substantially as described.

2. An extension-nozzle for sprayers having a liquid-tube, a pair of fittings secured to the ends of said tube, a sheathing surrounding the 100 tube and extending from one to the other of said fittings, and a ductile ring or collar secured to one of said fittings and having a portion deflected inward and in contact with the sheathing, substantially as described. 105

3. An extension-nozzle for sprayers having a liquid-tube, a pair of fittings secured to the ends of said tube, a sheathing surrounding the tube and extending from one to the other of said fittings, and an annular collar secured 110 to one of said fittings and having its margin spun or crimped inward into engagement with the sheathing, substantially as described.

4. An extension-nozzle for sprayers having a liquid-tube, a pair of fittings connected with 115 the ends of said tube, one of said fittings having a tapering nipple and a flange surrounding said nipple, a sheathing surrounding the tube and extending from one to the other of said fittings, one end of said sheathing being 120 fitted over the nipple, and means carried by the flange and engaging the sheathing for holding it in place, substantially as described.

5. An extension-nozzle for sprayers having a liquid-tube, a pair of fittings connected with 125 the ends of said tube, one of said fittings having a tapering nipple and a flange surrounding said nipple, a sheathing surrounding the tube and extending from one to the other of said fittings, one end of said sheathing being 130 fitted over the nipple, and a ring or collar of ductile material secured to the flange and

having a portion spun or crimped inward into engagement with the sheathing, substantially as described.

6. An extension-nozzle for sprayers having a liquid-tube, a pair of fittings secured to the ends of said tube, each of said fittings having a tapering nipple, a sheathing surrounding the tube and extending from one to the other of said fittings, the ends of said sheathing being fitted over the tapering nipple aforesaid, and rings or collars of ductile material secured to the fittings and having portions deflected inward into engagement with the sheathing for holding it, substantially as described.

7. An extension-nozzle for sprayers having a liquid-tube G, a fitting A having a bore into which one end of the tube is inserted and having a tapering nipple surrounding the tube, and an annular flange surrounding the nipple, leaving between them an annular recess, means for securing the tube in place in the bore of the fitting, a sheathing surrounding

the tube and having one end fitted over the nipple, and an annular ring or collar of ductile material secured to the flange and having a portion spun or crimped inward in engagement with the fitting, substantially as described.

8. An extension-nozzle for sprayers having a liquid-tube G, fittings A and F having bores into which projects means for securing the tube to the fittings, and a sheathing surrounding the tube and extending from one to the other of the fittings each of said fittings having a tapering nipple surrounding the tube, the ends of the sheathing being fitted over said nipples, and rings of ductile material secured to the fittings, and having portions deflected inward into engagement with the sheathing, substantially as described.
